UNITED STATES PATENT OFFICE

2,455,576

CURTAIN AND DRAPE MOUNTING

Vitantonio Fiorentino, Long Island City, N. Y.

Application December 13, 1946, Serial No. 715,845

2 Claims. (Cl. 211—105.3)

1

This invention relates to an improved mounting assembly adapted to be supported by a window frame for mounting curtains and/or drapes thereon and which is capable of use with window frames of various widths and which will greatly facilitate the application and removal of curtains and/or drapes.

Another object of the invention is to provide a mounting assembly of extremely simple construction and by means of which curtains or drapes or a combination thereof will be effectively supported in a manner to prevent sagging and to effectively prevent curtains or drapes from being accidentally released.

Still a further object of the invention is to provide a mounting assembly including curtain or drape supporting rods formed of extensible sections and having indicating means thereon for properly adjusting the sections as to length and before the curtains or drapes are applied thereto to enable the curtains or drapes to be correctly positioned on the supporting rods, preliminary to mounting the rods and to insure that the rods will be of correct length to permit their mounting without subsequent adjustments.

Various other objects and advantages of the invention will hereinafter become more fully apparent from the following description of the drawings, illustrating a preferred embodiment of the invention, and wherein:

Figure 1 is a fragmentary front elevational view looking toward the inner side of the upper portion of a window frame and showing parts of the mounting assembly applied thereto;

Figure 2 is a top plan view of the mounting assembly with two of the supporting rods removed;

Figure 3 is a vertical sectional view taken substantially along a plane as indicated by the line 3—3 of Figure 2;

Figure 4 is a vertical sectional view taken substantially along a plane as indicated by the line 4—4 of Figure 2;

Figure 5 is a transverse vertical sectional view taken substantially along a plane as indicated by the line 5—5 of Figure 2;

Figure 6 is a front elevational view of the left-hand bracket;

Figure 7 is a perspective view of the right-hand bracket;

Figure 8 is a perspective view of one of the right-hand supporting arms;

Figure 9 is a plan view, partly in section of one of the extensible supporting rods shown engaged by a pair of the supporting arms;

Figure 10 is a plan view of a portion of the blank

2

from which one of the sections of one of the supporting rods is formed;

Figure 11 is an end view in elevation of the inner end of one of the sections of one of the supporting rods;

Figure 12 is a similar view of the opposite end thereof and showing said last mentioned end partially formed;

Figure 13 is a view similar to Figure 12 but showing the rod end fully formed; and

Figure 14 is a fragmentary longitudinal sectional view taken substantially along a plane as indicated by the line 14—14 of Figure 13.

Referring more specifically to the drawings, the curtain and drape mounting assembly in its entirety is designated generally 15 and includes a left-hand bracket, designated generally 16 and a right-hand bracket, designated generally 17. The brackets 16 and 17 are each channel shaped in cross section and are adapted to be disposed in substantially horizontal alignment on the inner faces of the side rails 18 and 19 of a window frame 20 and adjacent the upper ends thereof. The brackets 16 and 17 are secured to the left and right hand frame rails 18 and 19, respectively, by suitable driven or screw fastenings 21 which extend through openings 22 in the web portions 23 thereof, for positioning the outer sides of said web portions substantially flush against the inner faces of the rails 18 and 19.

In the embodiment of the invention as illustrated, the top and bottom outwardly projecting flanges 24 and 25, respectively, of the brackets 16 and 17 are provided with three sets of aligned openings 26 which are disposed in longitudinally spaced relationship. The left-hand bracket 16 provides a support or mounting for three supporting arms 27, 28 and 29 having corresponding ends 30 and 31 and intermediate portions 32, 33 and 34, respectively. The intermediate portions 32, 33 and 34 differ from one another only in that the portion 33 is of a greater length than the portion 34 and the portion 32 is of a greater length than the portion 33, as clearly illustrated in Figure 2. The ends 30 of the supporting arms extend downwardly through the aligned openings 26 of the bracket 16 for supporting the intermediate portions 32, 33 and 34 in substantially horizontal planes and in outwardly projecting relationship to the bracket 16. The inner portions of the intermediate portions 32, 33 and 34 rest on the upper side of the upper flange 24. The ends 31 are turned inwardly at substantially right angles to the portions 32, 33 and 34 and are likewise disposed in substantially horizontal planes and sub-

stantially at right angles to the opposite ends 30. The largest supporting arm 21, as seen in Figure 2, is disposed adjacent the outer end of the bracket 16, the intermediate supporting arm 28 being disposed intermediate of the ends of the bracket 16 and the shortest supporting arm 29 being disposed adjacent the inner end of the bracket 16.

The bracket 17 supports three arms 27a, 28a and 29a, similarly mounted to the arms 27, 28 and 29 and differing therefrom only in that the ends 31a thereof extend in the opposite direction or inwardly and toward the ends 31, as clearly illustrated in Figure 2.

As best seen in Figures 1 and 2, the upper flanges 24 of the brackets 16 and 17 are provided, adjacent their free edges, with struck-up tongues or projections 35 which engage against the outer sides of the intermediate portions of the supporting arms for preventing said intermediate portions from swinging outwardly beyond positions substantially at right angles to the side rails 18 and 19.

The mounting means 15 also includes a plurality of supporting rods, designated generally 36, only one of which is illustrated, and which includes two telescoping sections, designated generally 37 and 38. The sections 37 and 38 are of substantially the same construction and differ from one another only in that the section 37 is larger in cross section than the section 38 so that the latter may telescope into the former. Each of the said sections is preferably formed from an elongated blank, as seen in Figure 10 of any suitable sheet metal or the like and which is folded along the longitudinal lines 39 to form a rod section of substantially triangular cross section, as seen in Figure 11 and which is provided with an overlying flange 40 which may be secured to the adjacent side, in any suitable manner. The outer end of each of the sections 37 and 38 are compressed along the edges thereof, as illustrated in Figure 12 to form the three equally spaced, two ply ribs 41 which combine to define a central opening 42. The ribs 41 are folded over in the same direction, as seen in Figure 13. The ends of the folded over ribs 41 will extend diagonally away from the opening 42 and the end portion, defining the opening is rolled inwardly upon itself, as illustrated in Figure 14 to provide a substantially smooth outer end for each of the rod sections 37 and 38. For the purpose of illustration, the thickness of the blanks from which the rod sections 37 and 38 are formed has been greatly exaggerated in the drawings. The blanks from which the sections are formed would ordinarily be very thin. As best seen in Figure 9, one side of the finished rod section 38 of each rod 36 is provided with a plurality of equally spaced graduations 43 provided with suitable calibrations, such as the numbers 44. It will be understood that the mounting 15 as illustrated in Figures 1 and 2 will employ three of the rods 36, one of which rods will be supported by the arms 27 and 27a, another by the arms 28 and 28a and the third by the arms 29 and 29a.

It will be readily apparent that the telescoping sections 37 and 38 enable the rods 36 to be adjusted for mounting on the various supporting arms and also for mounting in conjunction with

the supporting arms and brackets on windows of different widths. When initially mounted, the graduations 43 and their calibrations 44 are employed for indicating the correct extension of the rods 36 which are supported by having complementary arm ends 31 and 31a extend into the openings 42. This having been determined, a curtain, not shown, for example, can be mounted on a rod 36 and said rod thereafter engaged by the ends 31 and 31a of the supporting arms 29 and 29a. Said supporting arms are then applied to the brackets 16 and 17 for mounting the curtain therebetween and on the rod 36. By knowing in advance the proper extension of the rod sections, said sections can be adjusted before or after the curtain is applied to the rod but before the rod and arms are applied to the brackets 16 and 17 so that adjustment of the curtain on the rod can be accomplished before the curtain is hung. The supporting arms 28 and 28a are similarly utilized with the rod 36 for mounting window drapes and the arms 27 and 27a may be utilized with the rod 36 for mounting a top piece or border.

The tapered outer ends 41, 42 of the sections 37 and 38 are rounded and relatively smooth to permit said ends to be inserted in hems of curtains or drapes without danger of tearing.

It will be readily obvious that the brackets may be modified to support only one or two supporting arms, in which case one or two of the supporting arms of each of the brackets will be dispensed with and one or two rods 36 will likewise be omitted. Various other modifications and changes are likewise contemplated and may obviously be resorted to, without departing from the spirit or scope of the invention as hereinafter defined by the appended claims.

What is claimed as new is:

1. A curtain or drape supporting rod having tapered ends provided with supporting arm receiving openings, said rod being formed of hollow telescopic sections each of triangular cross section, and the outer end of each rod section being tapered and terminating in an inturned rolled edge forming the supporting arm receiving opening thereof.

2. A curtain or drape supporting rod as in claim 1, each of said rod sections being formed from a single blank of sheet material, and the tapered end of each rod section being formed by compressed folded over ribs constituting a part of said blank.

VITANTONIO FIORENTINO.
